UNITED STATES PATENT OFFICE.

JAMES F. DAVIS, OF STOCKTON, CALIFORNIA, ASSIGNOR OF ONE-HALF TO CHARLES H. SCHUMACHER, OF STOCKTON, CALIFORNIA.

REVERSIBLE RATCHET WRENCH.

Application filed April 16, 1924. Serial No. 706,801.

To all whom it may concern:

Be it known that I, JAMES F. DAVIS, a citizen of the United States, residing at Stockton, county of San Joaquin, State of California, have invented certain new and useful Improvements in a Reversible Ratchet Wrench; and I do declare the following to be a full, clear, and exact description of the same, reference being had to the accompanying drawings, and to the characters of reference marked thereon, which form a part of this application.

This invention relates to improvements in wrenches and particularly to that type commonly used in the automotive industry and by mechanics generally, and which comprises essentially a socket member for the nut or bolt-head, and a brace handle by means of which the socket member may be rapidly turned.

The principal object of my invention is to provide a reversible ratchet wrench attachment, in the form of a coupling to be interposed between the handle and socket members of such wrenches, and by means of which right or left hand ratchet movements of the handle relative to the socket may be had, or the socket may turn in unison with the handle as a practically rigid part thereof. The necessary adjustments to enable such different movements to be had may be made in an instant by the operator, without removing the socket or handle from the coupling, or without even having to remove the socket from a nut with which it may be engaged.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side view of the device.

Fig. 2 is a similar view, the control sleeve being in section, and showing the control member in position to cause the handle and socket members to turn as a unit.

Figs. 3 and 4 are similar views, showing the position of the control member to re-

spectively cause left and right hand ratchet movements of the handle relative to the socket member being had.

Fig. 5 is a view similar to Fig. 4, but with certain of the other parts of the device also in section.

Fig. 6 is an end view of the control sleeve and a sliding block therein, detached from the remaining parts.

Referring now more particularly to the characters of reference on the drawings, the numeral 1 denotes a tubular sleeve of certain length, and preferably cylindrical form, whose bore, intermediate its ends, is of polygonal sided form, as shown at 2, while the end bores are circular as shown at 3, and of somewhat greater diameter than the bore 2.

Slidably mounted in the sleeve 1, engaging the bore 2 and somewhat shorter than the same is a block 4, shaped to engage the faces of said bore, and having cut in its ends, radial and oppositely disposed right and left hand ratchet teeth 5 and 6 respectively.

Mounted in the sleeve at one end is a female or socket member 7, adapted to removably fit onto the end of a standard brace handle 8.

The outer portion of this member is circular and has both a sliding and turning fit in the circular bore 3 of the sleeve. The periphery of the inner portion of said member has the same polygonal sided contour as the central bore 2 of the sleeve, as shown at 9, the inner end of said portion 9 having ratchet teeth 10 to engage the teeth 5.

Mounted in the opposite end of the sleeve is a male member 11 similar to member 7, but having at its outer end a projecting boss or lug 12 adapted to removably fit into a standard wrench socket member 13.

The outer end of the member 11 has a sliding and turning fit in the outer bore 3 of the sleeve, while the inner portion has the same polygonal sided contour as the sleeve-bore 2, as shown at 14, and has at its inner end ratchet teeth 15 to engage the adjacent teeth 6 of the member 4.

The three members 4, 7, and 11 are permanently yet yieldably connected together, and the respective teeth normally held in engagement, by means of a pin or bolt 16 passing centrally through said members, one end of which bolt is screwed into the boss 12 while the head 17 on the other end is located

in an enlarged socket 18 provided in the member 7, a compression spring 19 being about the bolt between the head 17 and the opposite end of the socket 18.

5 The spring is capable of sufficient play to enable either set of coacting teeth on the various members to snap by each other when the sleeve is positioned relative to said members to allow of rotation of one of said members relative to the sleeve and central block 4 being had.

To hold the sleeve in definite yet movable relation to the members therein, the bores 3 are peripherally grooved as at 20 to form 15 seats for spring-pressed balls 21 mounted in the members 7 and 11.

In operation, to use the attachment as a "solid" wrench, that is with the handle 8 and socket member 13 turning as one, the sleeve 20 1 is moved to a central position relative to members 7, 4 and 11, as shown in Figs. 1 and 2. In this position, not only is the block 4 engaged by the polygonal sided bore 2, but the portions 9 and 14 of the members 25 7 and 11 are engaged therewith as well, so that the bore 2 forms a lock between the members 7, 4 and 11, preventing them from having any turning movement relative to each other, and they must therefore turn as 30 a unit.

If the sleeve is shifted toward the outer end of the member 7, as shown in Fig. 3, the members 7 and 4 are held locked, while the lock-bore 2 is drawn clear of the portion 14 35 of the member 11, and the latter is therefore free to turn relative to the sleeve and central block 4. The member 11 may then be intermittently turned in a continuous left-hand or counter-clockwise direction with a 40 reciprocating movement of the brace 8.

Similarly, if the sleeve is advanced toward the outer end of the member 11 as shown in Fig. 4, the members 4 and 11 are held locked together while the member 7 is 45 free to turn relative to the sleeve and block 4. The member 11 may then be intermittently turned in a right hand direction with a reciprocating movement of the brace 8.

From the foregoing description it will be 50 readily seen that I have produced such a device as substantially fulfills the objects of the invention as set forth herein.

While this specification sets forth in detail the present and preferred construction 55 of the device, still in practice such deviations from such detail may be resorted to as do not form a departure from the spirit of the invention, as defined by the appended claims.

60 Having thus described my invention what I claim as new and useful and desire to secure by Letters Patent is:

1. A reversible ratchet wrench attachment 65 comprising separate members adapted to be connected to handle and tool means respec-

tively, a block separable from and interposed therebetween, cooperating right- and left-hand ratchet teeth on the adjacent ends of the members and the block, means connecting said members and block in a manner 70 to yieldably hold all the cooperating teeth thereon in engagement, a sleeve about said members and block and slidably thereon, and means between the sleeve and said members and block whereby adjustment of the sleeve relative thereto will enable the said members and block to be held together to turn as a unit, and also to enable either at a time of the members to be held to turn with the block while permitting the other member to turn relative thereto.

2. A reversible ratchet wrench attachment comprising separate members adapted to be connected to handle and tool means respectively, a block separable from and interposed therebetween, cooperating right- and left-hand ratchet teeth on the adjacent ends of the members and the block, means connecting said members and block in a manner 85 to yieldably hold all the cooperating teeth thereon in engagement, a sleeve about said members and block and slidably thereon, the block being non-turnably mounted in the sleeve, and means between the sleeve and said members whereby with a certain position of the sleeve relative to the block both members are held to turn therewith, and with other positions of the sleeve one or the other only of said members is held to turn with the sleeve while the other member may turn relative thereto.

3. A reversible ratchet wrench attachment comprising separate members adapted to be connected to handle and tool means respectively, an independent block therebetween, cooperating right and left hand ratchet teeth on the adjacent ends of the members and the block, means connecting said members and block in a manner to yieldably hold the cooperating teeth thereon in engagement, a sleeve about said members and block and slidably thereon, said sleeve having a hollow polygonal portion extending axially therethrough intermediate its ends, 100 said portion being of greater length than the block and the block and the adjacent ends of the members slidably fitting therein, the latter being turnable in the sleeve bore outwardly of said polygonal portion, whereby when the sleeve is slid along to move said portion clear of a member, said member is free to turn relative to the sleeve and block.

4. A reversible ratchet wrench comprising 105 separate members adapted to be connected to handle and tool means respectively, an independent block therebetween, cooperating right- and left-hand ratchet teeth on the adjacent ends of the members and block, 110 spring means yieldably holding the coop- 115

erating teeth in constant engagement, a sleeve in which the block is slidably but non-
turnably mounted, said sleeve extending be-
yond the block to partially overhang the
5 end members, and means between the sleeve
and end members whereby with different
adjustments of the sleeve along the block,

the block and end members may turn as a
unit, or either at a time of the members may
be held to turn with the block while the 10
other member turns relative thereto.

In testimony whereof I affix my signature.

JAMES F. DAVIS.
